UNITED STATES PATENT OFFICE.

HARRY H. McCOLLUM, OF CRYSTAL LAKE, ILLINOIS.

GAS-LIGHTING APPARATUS.

1,216,824.

Specification of Letters Patent. Patented Feb. 20, 1917.

Application filed October 19, 1915. Serial No. 56,659.

To all whom it may concern:

Be it known that I, HARRY H. McCOLLUM, a citizen of the United States, residing at Crystal Lake, in the county of McHenry and State of Illinois, have invented certain new and useful Improvements in Gas-Lighting Apparatus, of which the following is a specification.

My invention relates to improvements in 10 gas lighting apparatus and more particularly to a control by means of which gas burners may be lighted or extinguished from a remote point.

One of the objects of my invention is the 15 provision of means for lighting and extinguishing gas burners positioned at inaccessible places, such for example, as in street lamp posts, lighting fixtures for churches, public halls, and other places having high 20 ceilings where the burners must necessarily be placed for efficient lighting at points not readily accessible.

Another object of my invention is the provision of apparatus by means of which a 25 series of lamps may be lighted or extinguished from a single control point.

Other objects of my invention are the provision of apparatus which will be positive 30 in its operation, simple and inexpensive to construct, and not liable to derangement.

Other and further objects will become apparent to those skilled in the art from a consideration of the following description and drawings, wherein:

35 Figure 1 is a vertical sectional view through the head of a street lamp showing my improved apparatus.

Fig. 2 is a horizontal sectional view on the line 2—2 of Fig. 1.

40 Fig. 3 is a horizontal sectional view on the line 3—3 of Fig. 1.

Fig. 4 is a horizontal sectional view on the line 4—4 of Fig. 1.

45 Fig. 5 is a horizontal sectional view on the broken line 5—5 of Fig. 1.

Fig. 6 is a vertical fragmentary sectional view on the line 6—6 of Fig. 5.

50 Fig. 7 is a fragmentary vertical sectional view on the line 7—7 of Fig. 1.

Fig. 8 is a side elevation of a lamp post embodying my invention with a portion of the base broken away.

Fig. 9 is a fragmentary side elevation of the pilot-light actuating valve, and;

55 Fig. 10 is an enlarged fragmentary ver-

tical sectional view through the pilot-light igniting burner.

In the particular embodiment of my invention, one embodiment of which is illustrated for the purpose of clear disclosure in the annexed drawings, the apparatus comprises in general a main gas valve for completely opening or completely closing connection between the gas main and the burners together with an auxiliary valve which feeds a pilot-light and maintains the same normally burning with a very small flame. In connection with these two valves I have provided an electro-magnetically actuated device on the operation of which the main valve is completely opened, assuming the valve to have been previously closed, and at the same time the pilot burner valve is opened wide throwing a jet of flame across the top of the main burners and igniting them. The solenoids by means of which the valves are actuated are included in a circuit comprising a battery and switch, the latter being located at any point convenient for operation. The same electrical circuit may actuate a plurality of burners, their solenoids being connected in parallel or otherwise.

The apparatus is so arranged that the initial movement of the solenoid actuated parts opens wide the main burner gas valve and the opening of the pilot burner valve, by means of which an impulse of gas is permitted to flow to the pilot lamp producing a projection of flame for igniting the main burners, takes place at the end or nearly at the end of the movement of the solenoid actuated part. This arrangement insures the proper flow of gas into the main burners before the lighting device comes into action, preventing back-firing.

Referring to the drawings wherein I have illustrated my invention as applied to a single unit multiple burner gas lamp such as is used for street lighting, the numeral 20 indicates the supporting post rising upwardly from a hollow base 21 and carrying at its top a head 22 on which the globe 23 is detachably mounted. A gas pipe 24 extends upwardly through the post 20, carrying at its upper end a star shaped distributing header 25 at the ends of the six arms of which are mounted the burners 26. In the present instance these burners are shown as of the ordinary Welsbach type using incan.

descent gas mantles 27, inclosed within glass chimneys 28.

I have interposed in the main gas pipe 24 at a point near its upper end and within the head 22 a main gas valve indicated in general by the numeral 29. This valve is supported by the arms 29' and comprises a casing 30 having screw threaded openings in its ends for connection in the main gas pipe 24. 10 Near the center of the casing 30 is provided a transversely opening recess 31, the inner end of which is tapered to receive the tapered gas controlling valve 32. This valve is of mush-room shape having a projecting stem 33 by means of which it is rotated. A port 34 provides communication between the chamber 31, at the rear of the valve 32, and the gas supply pipe 24 connected with the main. A port 35 communicates with the upper section of the pipe 24 leading to the burners and opens at its lower end to the tapered inner portion of the chamber 31 over which the valve head 32 contacts. A series of four diametrically spaced ports 36 are provided in the valve head 32 and adapted to open communication between the ports 34 and 35, when any one of the ports 36 register with port 35.

The valve actuating mechanism is so arranged that on a complete oscillation thereof the valve head 32 is rotated through one eighth of a revolution, each movement being progressively in the same direction and alternately covering and uncovering the port 35. A bushing 36 is screw threaded into the mouth of the orifice 31 and carries a rotatable shaft 37 flanged at its inner end to overlie the inner end of the bushing and recessed to receive the valve stem 33. Connection is made between the shaft 37 and the valve stem 33 by the slot and pin shown at 38. A coil spring 39 surrounds the valve stem 33 and has abutment at one end against the mushroom head of the valve and at the other end against the flanged out end of the shaft 37, thus insuring a tight fit between the valve and its seat.

The valve actuating mechanism is supported on a framework carried on the outer end of the bushing 36. This comprises a vertical post 40 secured to the outer end of the bushing 36 and a second post 41 parallel thereto and spaced away therefrom by means of the cross pieces 42-42. Screws 43 secure the posts 40-41 to the cross pieces 42-42.

On the outer end of the shaft 37 I have mounted a ratchet wheel 44 having formed around its periphery eight equi-distant pawl receiving notches 45.

60 The electro-magnetically actuated oscillatable member to which I have previously referred as furnishing the motive power for actuation of the valves comprises a pair of hollow arcuate solenoids 46-46 supported at their upper ends upon the bracket 47

which projects from and is integral with the post 40. A cross arm 48 carrying at its center a pivot pin 49 has mounted on its lower end 50 a pair of arcuate iron cores 51 arranged to telescope within the solenoids. 70 The outer end of the pivot pin 49 finds bearing in the post 41 whereas its opposite end is journaled within a bushing 54 screw threaded into the outer end of the stud shaft 37. The outer end of the bushing 54 is flanged 75 to overlie the ratchet wheel 44 and is diametrically slotted for engagement by a screw driver. A counter-weight 52 is carried at the opposite end of the arm, to partially counter-balance the weight of the cores 51-51 and a coil spring 53 surrounds the pivot pin 49, and has one end fixed on the post 41 and the other end positioned to overlie the cross arm 48 to insure its return to normal position on the deenergization of the 80 solenoids.

A pawl 55 is pivotally connected with the arm 48 for engagement with the teeth of the ratchet wheel 44. The oscillatory movement of the cross arm 48 is limited to substantially one eighth of a revolution, so that on each oscillation the ratchet wheel and its connected valve member is moved forward through an arc of 45 degrees.

To insure against retrograde movement 95 of the ratchet wheel and valve I have mounted upon the stationary arm 47, a second pawl 56 for engagement with the notches in the ratchet wheel.

It will be obvious that the apparatus thus far described will serve to alternately open and close the main gas valve upon oscillations of the magnetically actuated arm 48. In order, however, to insure the proper lighting of the burners after the main valve is opened, I have provided a pilot light with controlling valve which is automatically actuated subsequent to the opening of the main valve. This portion of the apparatus comprises a small burner 57 mounted at the 100 center of the cluster of main burners 26 and at a point elevated somewhat above the tops of the chimneys 28. Surrounding the burner 57 is a cylindrical shield 58 provided with holes 59 through which the six jets from the pilot flame, issuing from the corresponding orifices 60, spurt when the pilot burner valve is opened projecting the jets of flame across the tops of the chimneys 28 and igniting the gas flowing through the burners 26.

The supply pipe 61 for the pilot burner leads downwardly through a valve indicated in general by the numeral 62 and into casing 30 at a point beneath the valve 29 so as to be constantly in communication with the main supply, irrespective of the position occupied by the valve 29. The valve 62 is carried on a bracket 63 mounted at one side of the casing 30 and comprises a taper 115 120 125 130

plug 64 transversely drilled as at 65 to provide a gas passage. An arm 66 having oppositely extending wings 67 and 67' is carried on the outer end of the tapered plug 64. 5 A pin 68 carried on the arm 48 projects into the plane of the wing 67 so that when the solenoid draws the rod 51 upwardly the pin 68 will engage with the wing 67 and swing the valve into open position. Its return 10 to normal position is insured by the engagement of leaf spring 69 carried by the arm 66 with a pin 70 in the bracket 63. In order that the valve may be returned to a definite selected position by the spring 69 I have 15 provided a set screw 71 which passes through the horizontal flange of the bracket 63 and engages the inturned end of the wing 67', thus limiting the closure of the valve to any desired extent. Normally the valve will be 20 in a position as illustrated in Fig. 6 permitting always a slight flow of gas through to the pilot burner. The flame is thus maintained at a very low point only sufficient gas being admitted to prevent its accidental 25 extinguishment. The rapid opening of the pilot burner valve at or nearly at the end of the stroke of the magnetically actuated arm 48 insures a sudden rush of gas through and into the pilot burner causing spurts of 30 flame to project across the tops of the chimneys 28 igniting the main burners. On the return of the arm 48 to its normal position under the action of the spring 53 the pilot burner valve will, of course, be returned to 35 its normal adjusted position by means of the leaf spring 69, insuring the cutting down of the flame within the pilot burner.

The electrical circuit which I have illustrated for the operation of my device is very 40 simple, comprising the two wires 73 and 74 leading from solenoids 46, one being connected directly to one terminal of the battery cell 75 and the other leading to the other terminal of the battery cell 75 through the 45 switch 76. Closure of the switch energizes the solenoid and causes the actuation of the

valve either to light or extinguish the main burner depending upon its previous condition. Obviously other lamp lighting apparatus may be connected in circuit with the 50 switch and battery and simultaneously actuated.

Whereas I have illustrated and described the parts of this particular embodiment of my invention somewhat in detail, it is obvious that various changes may be made without departing from the spirit and scope of the appended claim. 55

Having described my invention, what I claim is: 60

An apparatus of the character described comprising a main valve casing; a gas supply pipe connected to the lower part thereof; a pipe connected to the upper part thereof; a star-shaped casing connected to 65 said upper pipe; a gas burner connected to each arm of said star-shaped casing, each burner carrying a substantially transparent chimney; a pilot-light pipe connected to the gas supply pipe below the main valve and 70 extending upwardly between said chimneys; a shield perforated for each burner carried by said pilot-light pipe; a pilot burner within the shield having an orifice for each main burner, registering with the perforations in the shield; a main valve in said main-valve casing; means for automatically opening the main valve and temporarily opening the pilot valve to increase the flow of gas from the pilot burners to ignite the 80 gas from the main burners above the chimneys and a spring to subsequently partially close said pilot valve after the main burners have been lighted. 75

In testimony whereof I hereunto set my 85 hand in the presence of two subscribing witnesses.

HARRY H. McCOLLUM.
